UNITED STATES PATENT OFFICE

156,417

FRUIT JUICE MIXER AND DISPENSER

Monroe Harrison, Chicago, Ill.

Application June 30, 1948, Serial No. 147,289

Term of patent 3½ years

(Cl. D44—1)

To all whom it may concern:

Be it known that I, Monroe Harrison, a citizen of the United States, residing at Chicago, Illinois, have invented a new, original, and ornamental Design for a Fruit Juice Mixer and Dispenser, of which the following is a specification, reference being had to the accompanying drawing, forming a part thereof.

In the drawing:

I claim:

The ornamental design for a fruit juice mixer and dispenser, substantially as shown.

MONROE HARRISON,
